UNITED STATES PATENT OFFICE.

DANIEL C. RIPLEY, OF PITTSBURG, PENNSYLVANIA.

FRUIT-BOWL.

SPECIFICATION forming part of Letters Patent No. 296,457, dated April 8, 1884.

Application filed December 20, 1883. (No model.)

To all whom it may concern:

Be it known that I, DANIEL C. RIPLEY, of Pittsburgh, in the county of Allegheny and State of Pennsylvania, have invented a new and useful Improvement in Fruit-Bowls; and I do hereby declare the following to be a full, clear, and exact description thereof, reference being had to the accompanying drawings, forming part of this specification, in which—

10 Figure 1 is a side elevation of my improved glass fruit basket or dish, and Fig. 2 is a vertical section of the same.

Like letters of reference indicate like parts in each.

15 The glass bowl *a* is pressed in a mold in the usual manner, and is preferably provided with a flange, *a'*, and a screw-peg, *a''*.

At two opposite points in the flange *a'* are holes *b*, extending through the flange, which 20 may be formed at the time of pressing the article or subsequently, as may be desired.

Secured to the dish by screws *c*, extending through the holes, are bail-lugs *d*, which are provided with threaded sockets *d'* for the reception of the screws *c*. The lugs *d* are provided with holes *d''* for the reception of the pivots of the swinging bail *e*. These pivots may be formed by turning the ends of the bail out, as shown in the drawings, or by turning 25 the ends inward, as may be desired. In the latter case the holes *d''* for the reception of the pivots would be in the outer side of the bail-lugs instead of in the inner side, as shown. I do not limit myself to this particular mode 30 of securing the bail-lugs to the glass dish herein described. Instead of the screw *c*, the lugs may be provided with threaded stems extending through holes *b* and secured by a nut on

the other side of the glass, or by upsetting the end of the stem, or by keys or other fastening devices. Nor do I limit myself to attaching the lugs to a horizontal flange, as they may be secured to the vertical side of the dish. The dish is provided with a metallic stem and foot, *g*, which is secured thereto by the screw-peg *a''*. 45

If preferred, the foot and stem *g* may be made of glass and secured to the bowl *a* by a ferrule, or it may be made in one piece with the bowl, or it may be omitted.

By my invention I secure a glass fruit basket or bowl having a pivoted bail or handle, which, when the dish is placed on the table, can be laid down flat on its edge. It constitutes a tasty and convenient article, and has the advantage over dishes with rigid bails of occupying less space and being less liable to be overturned as there is no danger of striking the handle, which would be the case if it were rigid and stood in a vertical position. The metallic lugs take the wear, strain, and 55 wedging action off the glass, and hence enable me to make use of the pivoted bail or handle without endangering the safety of the fragile glass bowl.

What I claim, and desire to secure by Letters Patent, is—

A glass dish or bowl having a pivoted metallic bail or handle secured thereto by metallic lugs, substantially as and for the purposes described.

In testimony whereof I have hereunto set my hand this 5th day of December, A. D. 1883.

DANIEL C. RIPLEY.
